SHAVING DEVICE

Mathew Andis, Racine, Wis.

Application April 6, 1938, Serial No. 200,391

3 Claims. (Cl. 30—43)

This invention relates to improvements in shaving devices.

The invention relates more particularly to shaving devices of the type having a reciprocating cutter, driven by an electric motor or other suitable means and movable beneath a slotted face engaging part of fixed blade, whereby the device may be used without soap or other beard-softening agent to greatly facilitate the shaving 10 operation.

In devices of this type, shaving is accomplished by a shearing action between the fixed blade and reciprocally movable cutter, and the closeness of the shave depends upon the thinness of the 15 slotted portion of the fixed blade. Heretofore various efforts have been made to obtain the desired thinness at said slotted portion, but several problems have been encountered. First, it is commercially impractical to cut slots in blades 20 formed entirely of extremely thin metal, such as metal of the safety razor blade type; second, even if such slots could be cut, there is the danger of teeth formed in such metal breaking off during use; and third there is the difficulty during use, 25 of supporting extremely thin metal against flexing. In the closed type of razor head the metal forming the fixed blade is slotted entirely across the top of the head and is supported against flexing by integral side walls and by the cutter. 30 This permits the use of fairly thin material, but the metal is still too thick to produce the closest type of shave. In other types of shavers a rigid self supporting face engaging member or fixed blade is employed, and there is therefore no 35 danger of flexing or breaking. However, in this type of construction the metal is usually uniformly tapered to a sharp edge, and the slots extend inwardly from said edge. This construction is objectionable because unless the hair is 40 cut off at the very edge of the member, then it is not cut off close because of the rapidly increasing thickness of the material which separates the base of the hair from the point of shear. This tapered construction was heretofore considered 45 necessary in a rigid type of blade because with the long slot heretofore employed, the metal had to increase in thickness to furnish the necessary support and to prevent the relatively long teeth from breaking off. In all devices where 50 the metal is of uniform thickness throughout the length of the slots, either a desired thinness must be sacrificed or supporting means must be furnished, and as before pointed out even where supporting means is furnished, there is a definite 55 limit to the thinness of material which it is com-

mercially practical to use. For example, in Schick Patent No. 1,757,978 the thickness is stated as .020 of an inch, whereas this is many times the thickness contemplated and made possible by the present invention.

It is an object of the present invention to provide a shaving device wherein the fixed blade is of a rigid self supporting type and wherein said blade departs from standard practice by having an edge ground to uniform wafer thinness for 10 such a limited distance inwardly that said thin edge cannot flex to any objectionable degree, there being slots in said edge which preferably terminate approximately at the end of said area of uniform thinness, the material progressively 15 increasing in thickness to furnish support for said extremely thin slotted edge. By having a uniform thinness of material throughout the length of the teeth, a close cut is assured, as distinguished from structures wherein the thickness 20 of material increases progressively from the edge, and by having the teeth very short, said area of uniform thinness can be obtained without danger of the slotted edge breaking. Furthermore, no extra support is necessary for the teeth because 25 they are too short to flex to any objectionable degree and are well supported by the increased thickness of the remainder of the rigid blade.

While it is preferred to have the teeth of the 30 fixed cutter no longer than the depth of the area of uniform thinness, the results can nevertheless be obtained by other means, such as by having the slots of the reciprocal cutter no longer than the depth of the area of thinness, because with either method cutting must take place at the area 35 of uniform thinness; and the present invention contemplates a very short area of uniform thinness together with means to insure cutting at said area.

A further object of the invention is to provide 40 a shaving device as above described wherein the ends of the slots between teeth in the fixed blade terminate at or ahead of the ends of the slots of the reciprocal cutter to hold the hair erect while it is being sheared.

With the above and other objects in view, the 45 invention consists of the improved shaving device and all its parts and combinations as set forth in the claims and all equivalents thereof.

In the accompanying drawing illustrating one 50 complete embodiment of the preferred form of the invention in which the same reference numerals designate the same parts in all of the views:

Fig. 1 is a side view of a shaving device em- 55

bodying the improved invention, part of the handle being broken away;

Fig. 2 is a top view of the head showing part of the handle attached thereto;

5 Fig. 3 is a fragmentary plan view of the fixed blade or face engaging member on an exaggerated scale;

Fig. 4 is a sectional view taken on line 4—4 of Fig. 3;

10 Fig. 5 is a fragmentary sectional view similar to Fig. 4 showing the portion of the cutter in co-operation with the fixed blades and illustrating a hair held erect by the end 40 of the slot of the fixed blade by which it is being cut; and

15 Fig. 6 is a view similar to Fig. 5 showing an alternative method of insuring cutting at the area of uniform thinness.

Referring more particularly to the drawing, the numeral 25 designates a hollow handle portion 20 formed of any suitable material and forming a housing for an electric motor and associated mechanism utilized to cause reciprocation of a movable cutter 26. The mechanism for driving the cutter may be of the type illustrated in co-pending application Serial No. 124,417, filed February 6, 1937. The handle portion may be closed by a removable cover 27, which cover has its end edge recessed throughout its length to receive an elongated strip of felt or other material 28.

25 The felt may be held in position in the cover by adhesives or any other suitable means. As illustrated in the drawing, the felt is of sufficient width so that it may be bent outwardly beneath the movable cutter 26 to frictionally engage the bottom of the same. A seal is thus formed to prevent cut hair from working beneath the cutter into the handle portion.

30 The fixed blade or face engaging member 29 is generally of rectangular outline and is formed for the most part of relatively thick metal whereby the blade is of a rigid self supporting type. The rear portion of the blade is provided with a pair of counter-sunk bolt holes 30 whereby the member may be secured to the handle by bolts 31. Intermediate its length the face engaging member 35 is preferably formed with an offset 32, but beyond said offset the outer surface is substantially flat as at 33, and slightly converging with respect to the corresponding lower surface 34.

35 Referring now more particularly to Fig. 4 which shows on an exaggerated scale the forward portion of the fixed blade, the lower surface of the blade is ground at an angle from the point 35 to the free edge of the blade. The upper surface is preferably concavely ground from the point 36 to the point 37. From the point 37 to the edge the upper surface is so ground as to provide a uniform thinness of material from the point 37 to the edge. Said area of uniform thinness has a depth equal to the distance (a) and it is preferred that said distance be approximately .025 of an inch and not greater than .050 of an inch. This uniformly thin area adjacent the edge has teeth 38 cut therein, which teeth are separated by slots 39 which end at 40. The teeth end approximately at the end of the area of uniform thinness, and the distance (a) must extend inwardly for such a limited distance that the very thin edge cannot flex to any objectionable degree. By having a uniform thinness of material throughout the length of the area at which the hair is cut, a close cut is assured as distinguished from structures wherein the thickness of material increases progressively 70 from the edge, and by having the teeth very

short, said area of uniform thinness can be obtained without danger of the slotted edge breaking. Furthermore, no extra support is necessary for the teeth because even though formed in extremely thin metal, they are too short to flex to any objectionable degree and are well supported by the increased thickness of the remainder of the rigid blade.

10 In order to obtain the desired results, the metal at the area (a) has a thickness of approximately .0025 of an inch and not greater than .003 of an inch. The pitch of the teeth is approximately .030 of an inch to obtain best results.

15 The free edge of the movable cutter 26 is formed with a plurality of spaced teeth 41 separated by slots which, in the preferred form of the invention, terminate at or behind the ends of the slots of the fixed blade as at 42. The teeth 41 of the cutter are movable below the teeth 38 of the fixed blade 29 and adjacent the free edge 20 thereof. When the electric motor is energized the movable cutter 26 is reciprocated at a very rapid rate to cause shearing of hair extending through the slots 39 of the face engaging member. By having the slots 39 of the fixed blade 25 terminate at 40 which is at or ahead of the ends 42 of the slots of the cutter and in the thin area (a) hair 43 will be engaged by said ends 40 and held in an erect position while being cut as indicated in Fig. 5.

20 As an alternative, cutting in the area of uniform thinness may be insured even though the teeth of the fixed blade are somewhat longer than the depth of area of uniform thinness, by having the teeth of the reciprocal cutter terminate 35 at 42' (see Fig. 6) to provide a length no greater than the depth of the area of uniform thinness of the fixed blade, the ends 42' serving to hold the hair erect while in the area of uniform thinness and while shearing is taking place.

25 In order to guard the face from the free edge 40 of the face engaging member and from the movable cutter, it is desirable to utilize a guard or comb member 44 in advance of the free edge of the face engaging member. This comb member presents a smooth surface to the face and is preferably slotted as at 45 by slots which are substantially the same width as the slots 39 of the fixed blade and which serve to pick up and straighten out the hair on the face and guide 50 the same into the slots 39. The teeth between the slots of the comb member have their ends rounded as at 46 to present a smooth surface to the face. Extending at substantially right angles to the guard, and preferably formed integral 55 therewith are supporting arms 47 having bolt openings 48 therein through which bolts 49 extend to secure the guard to the handle. The openings 48 are of slightly larger diameter than the stems of the bolts 49 as set forth in co-pending application 183,599, filed January 6, 1938, whereby the guard may be adjustably moved to vary the width of the gap between the guard and the edge of the fixed blade and to vary the position of the upper edge of the guard with respect 60 to the line b. The guard is otherwise formed and constructed in the same manner as set forth in said co-pending application.

65 It is apparent that by having the fixed blade provided with an edge ground in the manner heretofore described, that extreme thinness may be obtained throughout the length of the teeth in a structure utilizing a rigid type, self supporting fixed blade. As a result of the wafer thinness of the material separating the base of the 75

hair from the point of shear, throughout the length of the teeth of the fixed blade, an extremely close cut is assured.

This construction may be utilized in connection with a single edge shaving device as illustrated, or in connection with a double edge shaving device such as the one shown in Figs. 11 to 22 of co-pending application 185,599.

While the teeth 38 of the fixed blade may extend inwardly beyond the area of uniform thinness, such greater length would serve no useful purpose, it being the concept of the present invention to have an area of uniform thinness which extends inwardly for such a limited distance that the material cannot flex, in combination with a shearing cooperation between the teeth of the cutter and the fixed blade which insures cutting only at said area of uniform thinness, and this can be accomplished either by having the slots of the fixed blade of no greater length than the depth of the area of uniform thinness as in Fig. 5, or by having the slots of the cutter of no greater length than the depth of said area as in Fig. 6.

25 Although only two forms of the invention have been shown and described, it is obvious that various changes and modifications may be made without departing from the spirit of the invention, and all of such changes are contemplated 30 as may come within the scope of the claims.

What I claim is:

1. In a shaving device having a reciprocally movable cutter member provided with slots, an outer blade member mounted above said cutter, 35 means connected to a portion of said blade for supporting the blade against movement, said blade having a free edge portion projecting beyond the supporting means, and said projecting portion being of sufficient thickness and rigidity 40 throughout the major portion of its length to support itself against flexing, said outer blade member having an outer surface portion adjacent said free edge ground concavely to gradually taper the thickness of the metal to not greater than .003 of an inch and having a portion of uniform 45 thinness not greater than .003 of an inch extending outwardly from said concavely ground portion, said portion of uniform thinness having slots positioned over the slots of the cutter member and extending over such a limited distance toward the free edge of the blade, not greater than .050 of an inch, that the teeth of said uniformly thin slotted portion will not break during 50 normal use in spite of the thinness of said portion.

55

2. In a shaving device having a reciprocally movable cutter member provided with slots, an outer blade member mounted above said cutter, means connected to a portion of said blade for supporting the blade against movement, said blade having a free edge portion projecting beyond the supporting means, and said projecting portion being of sufficient thickness and rigidity throughout the major portion of its length to support itself against flexing, said outer blade member having an outer surface portion adjacent said free edge ground concavely to gradually taper the thickness of the metal to not greater than .003 of an inch and having a portion of uniform thinness not greater than .003 of an inch extending outwardly from said concavely ground portion, said portion of uniform thinness having slots positioned over the slots of the cutter member and extending over such a limited distance toward the free edge of the blade, not greater than .050 of an inch, that the teeth of said uniformly thin slotted portion will not break during normal use in spite of the thinness of said portion, the slots of said outer blade member being of no greater length than the depth of said area of uniform thinness to insure all shearing of hair taking place in said area.

3. In a shaving device having a reciprocally movable cutter member provided with slots, an outer blade member mounted above said cutter, 30 means connected to a portion of said blade for supporting the blade against movement, said blade having a free edge portion projecting beyond the supporting means, and said projecting portion being of sufficient thickness and rigidity 35 throughout the major portion of its length to support itself against flexing, said outer blade member having an outer surface portion adjacent said free edge ground concavely and having a lower surface portion ground on a plane disposed at an angle to gradually taper the thickness of the metal to minimum thinness and having a portion of uniform thinness equal to said minimum extending outwardly from said concavely ground portion, the upper surface of said 40 portion of uniform minimum thinness being substantially parallel to the angularly ground lower surface, said uniformly thin portion having slots positioned over the slots of the cutter member and extending over such a limited distance to 45 toward the free edge of the blade that the teeth of said uniformly thin slotted portion will not break during normal use in spite of the thinness of said portion.

MATHEW ANDIS. 55
